UNITED STATES PATENT OFFICE.

ALBERT M. BROUDY, OF DYSART, PENNSYLVANIA.

CHECK-BOOK.

1,003,326.

Specification of Letters Patent. Patented Sept. 12, 1911

Application filed February 1, 1911. Serial No. 605,963.

To all whom it may concern:

Be it known that I, ALBERT M. BROUDY, a citizen of the United States of America, residing at Dysart, in the county of Cambria and State of Pennsylvania, have invented certain new and useful Improvements in Check-Books, of which the following is a specification, reference being had therein to the accompanying drawing.

10 This invention relates to check books, and the primary object of my invention is to provide a check with a perforated and gummed tab, whereby it can be easily and quickly attached to a letter or other sheet of paper without necessitating the use of pins, clips, or other fasteners.

Another object of the invention is the provision of means in connection with the stub of a check book whereby checks can be evenly and accurately replaced and connected to the stub of the book for future reference.

My invention aims to prevent checks that have been returned by banking or clearing house from being lost or soiled, the check book from which the checks are removed, having the stubs thereof adhesively coated or gummed, whereby the return checks can be easily, quickly and evenly mounted in the check book to maintain a record of what the checks have been used for and to serve functionally as receipts.

With this understanding of the broad aspect of my invention, reference will now be had to the drawing, wherein:—

Figure 1 is a perspective view of a check book in accordance with this invention, Fig. 2 is a plan of a portion of one of the leaves from the check book, Fig. 3 is a plan of a portion of a piece of paper to which one of the checks is attached, and Fig. 4 is a plan of a portion of one of the leaves of a check book showing a returned check attached thereto.

45 The reference numeral 1 denotes a suitable binding for a check book and in the binding there is mounted leaves or sheets, each leaf or sheet constituting a plurality of stubs 2 and detachable checks 3, the
50 checks being separated one from the other and from the stubs 2 through the medium of vertical perforations and longitudinal perforations 5. The inner ends of the
55 checks adjoining the stubs 2 are provided with tabs 6 having the rear sides thereof adhesively coated or gummed, said tabs be-

ing separated from the stubs 2 by cut semi-cylindrical scalloped edges 7, the scalloped edges being cut when providing the perforations 4 and 5, whereby when one of the checks are removed the tab will become a part of the detached check. 60

Each check adjacent to the perforated edge 4 thereof is provided with two marks 8 that are printed or otherwise provided as guide lines for a purpose that will herein-after appear. 65

The stub 2 from which the checks are removed has the under outer edge thereof adhesively coated or gummed, as at 9, and by simply moistening this adhesive material, the checks 3 can be placed in position to have the inner ends thereof adhesively connected to the under side of the stub from which it was originally removed, the position of the check 3 relatively to the stub being determined by the marks or guide lines 8, and it is through the medium of this guide line or mark that the checks can be evenly and accurately arranged between the binding 1 to present a book that can be easily handled and referred to after the returned checks have been mounted therein.

As shown in Fig. 3 of the drawing, a detached check can be easily attached to a letter sheet 10 through the medium of the gummed tabs 6. For instance, when inclosing a check in a letter, to prevent its accidental displacement or loss, the check can be easily attached to the letter sheet by the tab 6 and after having been received, it can be easily and quickly detached from the tab 6 by the perforations 4. The tab remaining upon the letter sheet indicates by any future reference thereto, that a check accompanied the letter, and after the check has been detached from the letter it is in its natural condition and is not torn or mutilated by any fastening devices.

After the check has been returned by the bank or clearing house to the original remitter, it can be easily attached to the stub 2 from which it was originally removed, and the attaching of the check to the stub is facilitated through the medium of the marks or guide lines 8, whereby after all the checks have been returned to their original stubs, the check book will present an even and neat appearance. 100 105

From the foregoing it will be observed that the following advantages are derived by constructing check books in accordance 110

with my invention. First, it is only necessary to perforate the sheet or page of the check book in the usual and ordinary manner; second, that means is provided as heretofore described for maintaining the checks uniform in length and in position when returned and attached to their original stubs; third, that the use of a perforated strip across the check, pins, clasps or other fastening means are eliminated, and fourth, that a check book in accordance with this invention can be constructed as cheaply as the present type of check book.

What I claim is:—

15 A check book comprising leaves, each of said leaves including a plurality of stubs, a plurality of detachable checks separated from each other by a longitudinally-extending row of perforations and separated from 20 the stubs by a transversely-extending row of perforations, a semi-circular tab for each

check, said tabs projecting from said transverse row of perforations and disconnected from the stubs, each of said tabs having a scalloped cut edge, said tabs being detachable from said checks, each of said checks adjacent to the perforated end thereof being provided with guide lines whereby said checks can be evenly attached to the stub from which it was originally removed, said tab having the rear side thereof gummed for detachably securing a check in position when separated from the check book, and said stub having the inner side thereof gummed for connecting a return check thereto.

In testimony whereof I affix my signature in the presence of two witnesses.

ALBERT M. BROUDY.
